UNITED STATES PATENT OFFICE

160,585

TIE RACK

Ernest Ferguson, Leominster, Mass.

Application November 28, 1949, Serial No. 6,291

Term of patent 14 years

(Cl. D33—8)

To all whom it may concern:

Be it known that Ernest Ferguson, a citizen of the United States, residing at Leominster, in the county of Worcester, State of Massachusetts, has invented a new, original, and ornamental Design for a Tie Rack, of which the following is a specification, reference being had to the accompanying drawing, forming part thereof.

Fig. 1 is a top plan view;

Fig. 2 is a view in front elevation; and

Fig. 3 is an end view of a tie rack showing my new design.

I claim:

The ornamental design for a tie rack, as shown.

ERNEST FERGUSON.
